UNITED STATES PATENT OFFICE.

WILLIAM T. JONES, OF NEW WESTMINSTER, CANADA.

FLOAT-STRINGER.

SPECIFICATION forming part of Letters Patent No. 692,671, dated February 4, 1902.

Application filed June 18, 1901. Serial No. 65,019. (No model.)

To all whom it may concern:

Be it known that I, WILLIAM T. JONES, a subject of the King of Great Britain, and a resident of New Westminster, in the Province of 5 British Columbia and Dominion of Canada, have invented a new and Improved Float-Stringer, of which the following is a full, clear, and exact description.

This invention relates to a device for stringing net-floats and the like; and it comprises a standard forming a sort of needle, at the upper end of which is an eye to receive the end of a cord, so that the floats may be placed one above the other over the needle and cord and 15 then removed with the cord, thus holding all the floats together on the cord.

This specification is a specific description of one form of the invention, while the claims are definitions of the actual scope thereof.

Reference is to be had to the accompanying drawings, forming a part of this specification, in which similar characters of reference indicate corresponding parts in all the views.

Figure 1 is a sectional view of the invention, showing the floats in section and parts broken away. Fig. 2 is a plan view of the invention, and Fig. 3 is a detail view of the upper end of one of the standards.

a indicates a suitable base. As here shown, 30 this base is provided with two needle-like standards *b*, which are fastened to the base and project upward in parallelism. The upper end of each standard *b* has a tapered slit *b'* therein. These standards may be of any 35 length desired, according to the number of floats to be strung.

c indicates the string, which has its ends fastened in the tapered slots *b'* of the standards *b*, and the string is passed down alongside of the respective standards, with the middle portion of the string extending across between them directly over the base *a*. The floats are then placed on the standards and over the string or cord, as indicated in Fig. 1, until the standards are entirely covered by the 45 floats. Then the ends of the strings may be disengaged from the slots *b'* and the floats lifted from the standards, at which time they will be held on the cord or string *c*.

Having thus described my invention, I 50 claim as new and desire to secure by Letters Patent—

1. A float-stringer, comprising a base and a needle-like standard attached to and having means at its upper end for the engagement of 55 a cord or string therewith.

2. A float-stringer, having a base and two needle-like standards extending side by side and provided at their upper ends with means for engaging respectively the ends of a cord, 60 so that the cord may extend down alongside of the standards with its middle portion crossing between them at their lower ends.

In testimony whereof I have signed my name to this specification in the presence of 65 two subscribing witnesses.

WILLIAM T. JONES.
